UNITED STATES PATENT OFFICE.

MELVIN D. KILMER, OF CLEVELAND, OHIO.

WIRE-CUTTING MACHINE.

Application filed April 28, 1927. Serial No. 187,239.

My invention relates to wire-cutting machines and particularly relates to machines of this character adaptable for handling many different sizes of wire, readily and easily adjustable for cutting wire of different lengths, combined with means for straightening the wire and for feeding the same in proper alignment with the cutting means.

The annexed drawings and the following 10 description set forth in detail certain means embodying my invention, such means disclosing, however, but one of the forms in which the principle of the invention may be illustrated.

15 In said annexed drawings:

Figure 1 is a side elevation of the complete machine for feeding, straightening and cutting the wire;

20 Figure 2 is a fragmentary vertical transverse section, upon an enlarged scale, taken in the plane indicated by the line II—II, Figure 1;

Figure 3 is an end elevation, taken from the right-hand side of Figure 1;

25 Figure 4 is a plan view of the complete machine;

Figure 5 is a view similar to Figure 4, upon an enlarged scale, of a portion of the wire-straightening means;

30 Figure 6 is an end elevation, taken from the plane indicated by the line VI—VI, Figure 5, of a portion of the wire-straightening means;

Figure 7 is a side elevation, taken from the 35 plane indicated by the line VII—VII, Figure 6, of a portion of the wire-straightening means;

Figure 8 is a vertical transverse section, upon an enlarged scale, taken in the plane indicated by the line VIII—VIII, Figure 1;

40 Figure 9 is a side elevation, upon an enlarged scale, of fragmentary portions of the wire-feeding portion of the machine, the view being taken from the plane indicated by the line IX—IX, Figure 3;

Figure 10 is a fragmentary plan section, taken in the planes indicated by the line X—X, Figure 9; and

50 Figure 11 is a fragmentary plan section, taken in the plane indicated by the line XI—XI, Figure 9.

55 Referring particularly to the annexed drawings in which the several parts are indicated by the same respective ordinals in the different views, I show a table or bench 1 which forms a support for a base 2 upon

which are secured castings 3 and 4 of wire-straightening, and wire-feeding and cutting mechanisms, 5 and 6, respectively. Referring particularly to Figures 1 and 4, the wire 7 is 60 procured from a reel or any other suitable body of wire (not shown) and is pulled through the wire-straightening mechanism 5 by a feed device, hereinafter fully described, attached to and forming a part of the wire-cutting means 6, and severed into wire-portions 7' of the desired length by means of a die 63 and knife 61 hereinafter fully described.

The wire-straightening means comprises 70 two series of cooperating rolls mounted in the casting 3, one series 8 having vertically-aligned axes, and the other series 9 having horizontally-aligned axes, as plainly shown in Figure 1. The vertical and horizontal 75 series of rolls each consists of a number of alternately staggered rolls, Figure 4, the rolls in the series 8 being indicated in one row by the ordinal 10 and in the alternately staggered row by the ordinal 11, the corresponding rolls of the series 9 being indicated by the ordinals 16 and 17. The two series of rolls 8 and 9 are similar, except that they are arranged relatively right-angular one to the other, and I shall describe the construction 80 and operation of the rolls of series 9 only, particularly referring to Figures 1, 4, 5, 6, 7 and 8. A roll 16 is mounted to rotate upon a pin 18 provided at one end with a nut adapted to slide in a slot 20 thus securing 90 said pin to the casting 3, the pin 18 intersecting a block 19 adapted to be vertically or horizontally adjusted, depending upon which series of rolls is concerned, in the casting 3 by means of opposed wing screws 21 95 and 22. The alternately staggered rolls 17 are similarly mounted and adjusted. Thus means are provided for independently adjusting the several rolls of the two series 8 and 9 for adjusting the two series as a whole 100 in relatively right-angular planes, both series being further laterally adjustable by reason of the means now to be described. It will be noted in Figure 4 that one end of the casting 3 is secured to the base 2 by means of bolts 13' intersecting elongated slots 13 formed in the casting 3. It will also be noted that the other end of the casting 3 is similarly adjustably secured by means of a single bolt 12' and an elongated slot 12. Furthermore, 110 adjustable means are provided for guiding the wire 7 into the straightening rolls. These

means comprise a plate 3' laterally adjustably secured to one end face of the casting 3 by means of a bolt 14' and an elongated slot 14 formed in said plate 3', Figure 6. Guide 5 rolls 15 are secured to a horizontally-aligned flange of the plate 3' by means of bolts 15'. It will be noted in Figure 6 that the plate 3' is adapted for adjustment within an elongated recess 3² formed on top of the casting 3 and at one end of the latter. The means described and shown provide effective mechanism for straightening the wire both vertically and horizontally and by very minute adjustments in the several planes so as to permit the same to be pulled in proper alignment with the cutting mechanism and the guides thereto now to be described.

A pair of adjustable cooperating feed rolls 26 and 27 are secured to substantially parallel but relatively adjustable shafts 40 and 28, Figure 2, mounted upon the casting 4 as hereinafter fully described. Only one of the rolls, viz, roll 27 is formed to accommodate the wire 7, the other roll 26 simply cooperating therewith to pinch and properly pull the wire, the accommodation afforded by the roll 27 consisting of a plurality of peripheral grooves 27', of different sizes to care for wires of different diameters. Secured to the outer ends of the respective shafts are cooperating gears 41 and 42 by means of which the positive rotation of the feed roll 26 is effected. The rotation of the main shaft 28 is effected by an operating handle 29, the actual connection between this handle and the shaft consisting of the following means. The hub of a ratchet wheel 30 is secured to the shaft 28, this ratchet wheel 30 cooperating with a spring-pressed pawl 31 secured by means of a bolt 33 to the handle 29. In order to provide for the feed of wire portions of different lengths, I secure to the base 2 by means of bolts 35, Figure 9, an annular plate 34 having two elongated slots 36 intersected by wing screws 37 provided with lock nuts 38 and extending inner ends 39 lying in the path of movement of the rib 32 formed on handle 29, as plainly shown in Figures 2, 9 and 10. It is evident that proper positioning of the wing screws 37 will provide the desired throw for the handle 29 so as to cause the feed rolls 26 and 27 to pull the desired length of wire from the reel and through the straightening devices 5. The mounting for the shafts 28 and 40 and means for vertically adjusting same are as follows. The shaft 28 is mounted in bearings 43 and 44 and the shaft 40 in bearings 45 and 46. These bearing members are slidably contained between vertical guides 47 to the top of which are secured longitudinal caps 49 by means of bolts 49', any excessively loose play between the bearings and slides 47 being eliminated through the medium of adjusting screws 55 provided with lock nuts 55'. The cap plates 49 are formed with raised internally-threaded bosses 50 intersected by and adapted to cooperate with screws 51 and 52 provided with lock nuts 51' and 52', respectively. These screws bear upon horizontally-aligned plates 48 contained within recesses 53 formed in the bosses 50 and held tightly up against the bottom ends of the screws 51 and 52 by means of coil springs 54 mounted upon the respective bearing blocks 45 and 46. It will be noted in Figure 2 that a clearance 77 is shown between the bearing blocks 45 and 46 and the bosses 50 whereby it is indicated that the shaft 40 and hence the feed roll 26 can be somewhat vertically adjusted to provide a varying pressure upon the wire 7 or to provide for feeding wire of varying diameter. Further vertical adjustment is provided between the bearing blocks 43 and 46, 44 and 45, respectively, by the following means. A bolt 56 intersects the casting 4 and is adapted to bear against and vertically adjust the bearing block 43, clearance being provided for this adjustment through the medium of a recess 2' formed in the base 2 and within which the head of the bolt 56 is contained. A second bolt 57 provided with a lock nut 58 bears against the undersurface of the bearing block 45 and is threaded into the upper surface of the opposed lower bearing block 44. These several means provide vertical adjustment for the feeding mechanism whereby the wire 7 is fed in proper alignment to cutting means now to be described and whereby the proper cooperation of the feed rolls 26 and 27 may be secured for feeding wire of varying diameters.

The cutting knife 61 is simply a suitable bar having a shear blade section and is pivoted at one end upon a bolt 64 to an upright bracket 62 secured to the casting 4. This bracket 62 is provided with a tubular hardened die 63 through which the wire 7 is forced and adjacent the outer exit end of which the wire portion 7' is severed from the main body of the wire. The knife 61 is operated either manually or by a treadle in the following manner. For treadle operation, a strap 69 is pivotally secured at one end to the spring-controlled treadle proper 70, this strap at its upper end being adjustably secured by means of a guide 67 and a set screw 68 to a link 65 which is bent at one end to pass around one side face of the knife 61 and cooperates with a second link or strap member 66 to form a U-shaped holder for the knife 61. The purpose of the adjustable feature provided by the members 65, 67 and 68 is to thereby enable the treadle 70 to be used at varying heights according to the desires or the convenient reach of the operator. For hand operation, the knife 61 is fastened by the bolt 71 in the position shown in dot-and-dash outline, Figure 3, this connection being adjacently below the hardened die 63 and the cutting edge for the wire hereinbefore

described with reference to the foot operation. It is evident that this connection permits the cutting bar 61 to be pulled toward the operator by hand operation in distinction to the foot operation whereby the cutting bar 61 is pulled away from the operator to effect the cutting of the wire.

What I claim is:

1. In a wire-cutting machine, wire-feeding means, including cooperative wire-receiving rolls, a shaft to which one roll is secured, an operating handle secured to said shaft for movement in one direction and free of said shaft for movement in the other direction, and means controlling the amount of reciprocable movement of said handle to determine the amount of wire to be fed; and means for cutting the wire.
2. In a wire-cutting machine, wire-feeding means, including cooperative wire-receiving rolls, a shaft to which one roll is secured, an operating handle secured to said shaft for movement in one direction and free of said shaft for movement in the other direction, and handle stops adapted to be fixed in selective positions to determine the amount of wire to be fed; and means for cutting the wire.
3. In a wire-cutting machine, wire-feeding means, including cooperative wire-receiving rolls, a shaft to which one roll is secured, an operating handle secured to said shaft for movement in one direction and free of said shaft for movement in the other direction, a fixed grooved segment, and stops adjustably mounted in the groove of said segment and positioned to intersect the path of movement of said handle upon both sides of the latter to determine the amount of wire to be fed; and means for cutting the wire.
4. In a wire-cutting machine, wire-feeding means, including cooperative wire-receiving rolls, a shaft to which one roll is secured, an operating handle rotatably mounted upon said shaft, a ratchet secured to said shaft; a cooperating pawl secured to said handle, a fixed segment axially-aligned with said shaft, a pair of spaced annular grooves being formed in said segment, a pair of stops adjustably mounted in said grooves, respectively, and having extended ends laying in the path of movement of said handle, the latter being positioned between said stops; and means for cutting the wire.
5. In a wire-cutting machine, a main frame; wire-straightening rolls mounted thereon; means for laterally adjusting said rolls; a transverse shaft; vertically-adjust-

able blocks mounted upon said frame and forming bearings for said shaft; a wire-feeding roll secured to said shaft; a cooperative feeding roll; means tending to hold said feeding rolls in wire-feeding position; means automatically adjusting the pressure of said second-named feeding roll upon the wire; means for cutting the wire; and wire-guiding means adjacent said cutting means, whereby the straightening means and the feeding means can be axially-aligned with the guiding means and with each other.

6. In a wire-cutting machine, a feeding device comprising a support; a vertically-adjustable block mounted thereon and forming a bearing; a shaft journalled in said bearing; a gear secured to said shaft; a second bearing block for said shaft; vertical slides for holding said bearing blocks; upper bearing blocks mounted in said slides; a second shaft journalled in said upper bearing blocks; coiled springs mounted upon and exerting downward pressure upon said upper blocks and means for adjusting the tension of said springs; a cooperative gear secured to said second shaft; and cooperative wire-feeding rolls secured to said shafts.

7. In a wire-cutting machine, a feeding device comprising a support; a frame mounted thereon and provided with two lower bearing members vertically adjustable therein; a shaft journalled in said bearings; a gear secured to said shaft; means for vertically adjusting one of said lower bearing members; upper bearing blocks vertically adjustably mounted in said frame; a second shaft journalled in said upper blocks; a cooperative gear secured to said second shaft; coiled springs mounted upon and exerting downward pressure upon said upper blocks and means for adjusting the tension of said springs; means adjustable in length for spacing the other lower bearing member and one of said upper bearing blocks; and cooperative wire-feeding rolls secured to said shafts.

8. A wire-cutting device comprising a support; a die mounted therein and formed with an upper wire-cutting edge and a lower wire-cutting edge; a cutting member; means for pivotally mounting the latter adjacently above said upper cutting edge; and means for selectively mounting said cutter adjacently below said lower cutting edge, whereby selective cutting by the movement of said cutting member in either direction is afforded.

Signed by me this 26th day of April, 1927.
MELVIN D. KILMER.
